(57) CLAIM

The ornamental design for a shoes storage bench, as shown and described.

DESCRIPTION

FIG. 1 is a front, left, top perspective view of a shoes storage bench, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, left, top perspective view thereof, with the doors in an open position.

The broken lines in the drawings illustrate the portions of the shoes storage bench, which form no part of the claimed design.
